CAM OPERATED ADJUSTABLE MICRO TIMING SWITCH

Lewis A. Kingsley, Beverly Hills, Calif. (½ Kingsley
Machine Co., 850 Cahuenga Blvd., Hollywood, Calif.)
Filed Sept. 11, 1961, Ser. No. 137,318
8 Claims. (Cl. 74—3.54)

This invention relates to an improved mechanism for accurate variable adjustment of the actuation of a switch or valve in mechanical co-ordination with the operation of a machine.

In many machines the operation of one element must be coordinated with the operation of another element, and further, often that coordination must be varied as to the relative timing of the operations as well as relative duration of those operations. It is also essential in some machines that this coordination be readily and accurately variable by the operator in response to changing conditions or requirements.

In the marking of wire, tubing and the like by a hot stamping machine such as described and illustrated in Patent No. 2,960,024 issued November 15, 1960, to me, and in my co-pending application Serial No. 756,814, filed August 25, 1958 (now Patent No. 2,996,000), and entitled Air-Operated Wire and Tube Marking Machine, the duration of contact between the heated stamp and the wire or tubing must be varied depending on the materials and temperatures in order to obtain the most desirable results. The particular coating on a wire may be adversely affected by prolonged contact with the heated stamp or conversely an insufficient period of contact may result in an unsatisfactory or non-permanent marking. To obtain the ideal duration of contact, it may be advisable to be able to vary that time period while the machine is in operation, thereby enabling a high standard of quality control of the marking and a minimum of imperfections.

It is therefore an object of this invention to provide a switch which may be coordinated with the movements of a machine and variable in its operation relative to that machine.

It is a further object of this invention to provide a switch or valve which is actuated by a cam on a machine and may be accurately adjusted.

It is a further and more detailed object of this invention to provide a switch for use on a hot marking machine to vary the duration of contact between the hot stamp and the workpiece which may be accurately adjusted and coordinated with the machine.

Other and more detailed objects and advantages of this invention will appear from the following description and the accompanying drawings:

In the drawings:

FIGURE 1 is a side elevation of the switch assembly constituting a preferred embodiment of my invention.

FIGURE 2 is an end elevation of the switch assembly taken substantially on the line 2—2 of FIG. 1.

FIGURE 3 is a sectional view taken substantially on the line 3—3 of FIG. 1.

FIGURE 4 is a sectional view of the microswitch and actuating cam taken substantially on line 4—4 of FIG. 2.

FIGURE 5 is a sectional view taken substantially on the line 5—5 of FIG. 3.

FIGURE 6 is a fragmentary elevational view similar to FIG. 4 illustrating a modification.

Referring to the drawings, the housing, generally designated 10, is comprised of a frame 11 which has side straps 12 and 13 secured to each side by any convenient means such as cap screws 14.

A shaft 15 is supported in bearing apertures 16 and 17, and is free to rotate relative to the frame 11. A worm

2

gear 18 is fixed to the shaft 15 in a position intermediate of the apertures 16 and 17 by set screw 19. In order to adjust the shaft 15 in an axial direction, as desired, an adjustment screw 20 having a conical point 21 on one end engages a conical depression 22 in one end of the shaft. The frame 11 is threaded at 23 for receiving the threaded portion of screw 20 and a lock nut 24 threaded onto screw 20 is provided for locking the screw in position after desired axial adjustment has been made.

5 Contact between the conical point 21 and conical depression 22 is maintained by a dish-shaped spring washer 25 received on the shaft 15 and compressed between an inner surface 26 of the frame 11 and the end 27 of the worm gear 18 by adjustment of screw 20. For manual

10 turning of the shaft 15, a handle 28 is secured to the free end by set screw 29. To permit visual settings or adjustments of the switch, a dial 30 is mounted on the frame, coaxial with shaft 15, by cap screw 31. A pin 32 on the dial face limits turning of the handle 28 by engaging the 20 pointer end 33 of the handle.

15 A second shaft 34 is mounted in the housing 10 and is to rotate in support bushing 35 pressed into an opening 36 on the side strap 13 and a support assembly, generally designated 37, mounted in threaded opening 38 in side strap 12. The support assembly 37 has a bushing 39 carrying the shaft 34 and is mounted in a threaded sleeve 40. The sleeve 40 is threaded into opening 38, and after proper adjustment, is locked in the desired position by lock nut 41.

20 In order to provide mechanical connection between shaft 15 and shaft 34, a worm wheel assembly, generally designated 42, engages the worm 18. The assembly 42 is comprised of two adjacent flanges 43 and 44, each with teeth 45 of the appropriate configuration for engagement 25 with the worm gear. The flange 44 is secured to shaft 34 by any convenient means such as pin 46, and the flange 43 is movable relative to shaft 34. Each flange has a pair of openings 47 and 48 with a finger 49 protruding laterally into each such opening. In order to urge opposite 30 relative turning of the flanges, coil springs 50 and 51 are positioned in the openings formed by the adjacent openings of the two flanges 43 and 44 and each spring has one end installed over the finger 49 of one flange and the other end installed over the finger 49 of the other flange.

35 In assembling the worm wheel assembly 42, the flange 43 is turned relative to the flange 44 and shaft 34 so as to compress the springs 50 and 51 and the teeth 45 are moved into engagement with the worm gear 18. As thus 40 assembled, the springs urge the teeth of one flange into engagement with one side of the teeth on the worm gear and urge the teeth of the other flange into engagement with the other side of the teeth on the worm gear.

The alignment of the worm wheel assembly 42 with the axis of the shaft 15 is maintained by the shoulder 52 45 of bushing 39 engaging the sleeve 40 to limit axial movement in one direction. A leaf-type spring 53 secured to strap 13 by an convenient means such as rivet 54 has a free end 55 slidably engaging one end 56 of flange 44 and urging that flange axially against flange 43 and thereby 50 urging flange 43 against the surface 57 of bushing 39.

To facilitate mounting of conventional switch, a block 58 is secured to shaft 34 by set screws 59. Any conventional switch such as micro-switch 60 is mounted on block 58 by means of cap screws 61 and is provided with a plunger 62 which makes or breaks an electrical circuit upon axial movement of the plunger. I prefer to use a 55 micro-switch which accomplishes this making and breaking with the minimum amount of required axial movement such as 0.002 of an inch, and the plunger 62 being capable 60 of further movement without affecting the circuit.

The plunger 62 is provided with a cam follower 63 for 65

70

engaging the cam 64. While any cam shape may be used, I prefer to use a circular cam eccentrically mounted on the rotating shaft 65 so that as the switch plunger 62 is moved progressively toward the cam shaft 65, the switch is actuated for progressively longer period of time for a given speed of rotation of shaft 65.

Movement of the plunger 62 and cam follower 63 toward and away from the cam shaft 65 is accomplished by turning the handle 28 clockwise and counterclockwise, respectively, as more or less of a time period in which the switch remains closed or open is desired. The plurality of biasing means 25, 50, 51 and 53 promote immediate responsive movement of the switch 60 upon the slightest movement of the handle 28.

Grooves 66 and 67 are provided in either side of the frame 11 for accommodating conventional clamping means (not shown) to fix the frame 11 to a frame member 68 of the machine carrying the shaft 65.

The switch 60 may be used to energize a solenoid or circuit whereby the required operation is accomplished, such as a solenoid operated air valve and the associated elements as described in my co-pending application Serial No. 756,814, filed August 25, 1958, and entitled Air-Operated Wire and Tube Marking Machine.

In the modification illustrated in FIGURE 6, an air valve 69a having an actuating plunger 62a and a cam follower 63a on the end of the plunger is mounted on the block 58 rather than the micro-switch 60 of my preferred embodiment. The air valve 69a is actuated by the cam 64 substantially the same as the micro-switch 60 is actuated as described above. The air permitted to pass through the valve 69a when actuated by the cam may be used to perform the desired operation in an air operated machine or to actuate valves to perform these operations.

While what hereinbefore has been described as the preferred embodiment of this invention, it is readily apparent that alterations and modifications may be resorted to without departing from the scope of this invention and such alterations and modifications are intended to be included within the scope of the appended claims.

I claim:

1. In an adjustable control unit operably responsive to a cam or other actuating means, the combination of: a turnable shaft, a switch means eccentrically mounted on said shaft, said switch means having means for engaging said cam or actuating means, a second shaft, and means connecting said first and second shafts.

2. In an adjustable control unit operably responsive to a cam or other actuating means, the combination of: a turnable shaft, a switch means eccentrically mounted on said shaft, said switch means having means for engaging said cam or actuating means, a second shaft, and means mechanically connecting said second shaft to said first shaft whereby movement of said second shaft causes turning of said first shaft.

3. In an adjustable control unit operably responsive to a cam or other actuating means, the combination of: a housing having two shafts rotatably mounted therein, gear means mechanically connecting said shafts whereby turning of the first shaft results in turning of the second shaft, switch means fixedly and eccentrically mounted to the said second shaft, and said switch means having an element for engaging the said associated cam or actuating means.

4. In an adjustable control unit operably responsive to a cam or other actuating means, the combination of: a housing having two shafts rotatably mounted therein, the first said shaft having worm gear fixedly mounted thereon, the second said shaft having a worm wheel gear fixedly mounted thereon, the said shafts positioned for interengagement of the said worm and worm wheel gears, a switch means fixedly and eccentrically mounted on the

5 said second shaft, and said switch means having an element for engaging the said associated cam or actuating means, whereby turning of the said second shaft moves the said element toward or away from the said cam or actuating means.

5. In an adjustable control unit operably responsive to a cam or other actuating means, the combination of: a housing having two shafts rotatably mounted therein, the first said shaft having a worm gear fixedly mounted thereon, the second said shaft having a worm wheel gear fixedly mounted thereon, the said shafts positioned for interengagement of the said worm and worm wheel, a switch means having a cam-engaging means for actuating the switch means, the said switch means being eccentrically mounted on the said second shaft whereby turning of the said second shaft moves the said cam-engaging means toward or away from the said associated cam or actuating means for actuating the switch means.

6. In an adjustable control unit operably responsive to a cam or other actuating means, the combination of: a housing having two shafts rotatably mounted therein, the first said shaft having a worm gear fixedly mounted thereon, the second said shaft having a worm wheel gear fixedly mounted thereon, the said shafts positioned for interengagement of the said worm and worm wheel, the said worm wheel gear having two adjacent flanges with substantially similar gear teeth, one of said flanges being secured to the said second shaft and the other flange being rotatably mounted on said second shaft, biasing means 20 extending between said flanges for urging opposed turning whereby both the leading and trailing sides of the worm gear teeth are engaged by the worm wheel, and a switch means having a cam-engaging means for actuating the switch means, the said switch means being eccentrically mounted on the said second shaft whereby turning of the said second shaft moves the said cam-engaging means toward or away from the said associated cam or actuating means for actuating the switch means.

7. In an adjustable control unit operably responsive to a cam or other actuating means, the combination of: a housing having two shafts rotatably mounted therein, the first said shaft having a worm gear fixedly mounted thereon, the second said shaft having a worm wheel gear fixedly mounted thereon, the said shafts positioned for interengagement of the worm and worm wheel, the said worm wheel gear having two adjacent flanges with substantially similar gear teeth, one of said flanges being secured to the said second shaft and the other flange being rotatably mounted on said second shaft, a pair of openings in each flange, a coil spring in each opening extending between one flange and the other flange for urging opposed turning whereby the leading sides of the worm gear teeth are engaged by one flange and the trailing sides of the gear teeth are engaged by the other flange of the worm wheel, a switch means having a cam-engaging means for actuating the switch means, and the said switch means being eccentrically mounted on the said second shaft whereby turning of the said second shaft moves the said cam-engaging means toward or away from the said associated cam or actuating means for actuating the switch means.

8. The combination of claim 7 wherein the coil springs extending between the two flanges of the worm wheel are in compression.
